UNITED STATES PATENT OFFICE

JOSEPH A. WADDELL AND JAMES W. FORESMAN, OF WILLIAMSPORT, PENNSYLVANIA,
ASSIGNORS TO SPENCER HEATER COMPANY, OF WILLIAMSPORT, PENNSYLVANIA,
A CORPORATION OF PENNSYLVANIA

SECTIONAL BOILER

Application filed August 29, 1928. Serial No. 302,814.

This invention relates to sectional steam boilers and has for its object to provide a device which is simple in construction and efficient in use.

5. With these and other objects in view the invention consists in the novel details of construction and combinations of parts as will be more fully hereinafter disclosed and particularly pointed out in the claims.
10. Referring to the accompanying drawings forming a part of this specification in which like numerals designate like parts in all the views:

Fig. 1 is an elevational view of one of the 15 sections used in constructing the steam boilers of this invention;

Fig. 2 is a detail elevational view taken as on the line 2—2 of Fig. 1 and looking in the direction of the arrows; and

20. Fig. 3 is a transverse sectional view taken as on the line 3—3 of Fig. 1 and looking in the direction of the arrows.

It is well known that efficient steam boilers are preferably constructed in units or sections, the plurality of units being secured together by suitable means to produce the complete heating plant. Further these boilers include a plurality of identical intermediate units, a front unit and a back unit, and 25 all of said units are so formed as to provide continuous conductive passages for the water of the boiler, as well as a continuous conduit for the steam generated from said water.

Such heretofore well known constructions 30. are exemplified in the U. S. Letters Patent No. 1,045,668 to D. Boies and J. A. Waddell, jr., entitled Sectional boiler and No. 1,063,088 granted to J. A. Waddell, jr., and entitled Water jacket furnace, the former disclosing 35 double grate construction wherein the fuel magazine is disposed centrally of the boiler intermediate of the water legs, and the latter patent disclosing a single grate boiler wherein the magazine is disposed on one side of 40 the boiler. This invention is directed to an

improvement over the construction shown in the last mentioned patent.

In Fig. 1 is shown in elevation one of the intermediate water sections of the boiler and which comprises a fuel magazine 5 disposed on one side of said section and immediately above a water leg 6 which is adapted to connect with the similar water leg of an adjacent section in a well known manner namely as by a nipple threaded into the passage 7. 50 On the other side of the section and forming one wall of the magazine space 5 is a chamber generally indicated by the numeral 8 having formed therethrough the flue passages 9 through which the gases of combustion 55 will travel as readily understood. This water chamber 8 has a depending portion 10 which is inclined from the vertical in a direction towards the inner inclined surface 11 of the water leg 6 to provide the constricted 60 throat 12 at the bottom of the fuel magazine 65 chamber.

At or near the top of the section and preferably centrally disposed thereof is the passage 13 threaded as indicated at 14 to receive 70 a nipple to connect said section with the one next adjacent. Within the chamber 8 and integrally cast with the walls thereof is a baffle plate 15 extending around the lowermost half of the passage 13 to prevent water 75 entrained with the steam entering said passage, whereby a steam substantially free of water is obtained from each section. 16 represents the normal level of liquid in the section. The chamber 8 communicates with a 80 vertical water leg 20 which extends to a point below the grate and has at its bottom a passage 21 threaded as at 22 to receive a nipple connecting the section with the one next adjacent. 23 is a hollow web connecting the 85 water leg 6 with the depending throat piece 10 associated with the chamber 8. The thickness of the web 23 is made such as to permit the coal from the magazine 5 to readily but moderately flow past the sides of said 90

web down through the throat 12 to the grate as will be readily understood by one skilled in the art.

Thus it will be seen that there is provided a substantially inverted U-shaped section having parallel sides each of which constitutes a water leg, and that these water legs are connected by the web chamber 23 and the upper chamber 8 where steam is evolved. 10 Further it will be seen that the plurality of sections may be readily assembled by nipples screwed into the water and steam passages 7, 13 and 21, the water passages 7 and 21 being disposed at the lowermost ends of the water 15 legs and the steam passage 13 being at the uppermost portion of the boiler. By such a construction the water is caused to circulate through the sections, when the passages 7 and 21 are connected, as will be readily understood by those skilled in the art. 20

Each of the boiler sections has integrally cast therewith supporting legs 25 of angle, T or other suitable cross-section which are disposed immediately below and in continuation 25 of the water legs 6 and 20, each of said supporting legs 25 being braced as at 26 by a web for added strength. Both sides of each intermediate section are similarly provided with an integrally cast narrow or thin outer standing rib 30 ground to provide a perfectly plane smooth surface so that when two adjacent sections are placed together the rib of one will register with the rib of the other, creating therebetween a joint which is sufficiently tight to prevent the escape of heat from the boiler as a whole. This rib starts at the bottom of one of the supporting legs 25, or in other words at the floor line, extends up said leg, entirely encircles the water passage such as 21 and extends upwardly and downwardly therefrom along the inner side of the water leg 20 to provide a closed firebox. Thence the rib extends diagonally across the water leg 20 and up along the outer side thereof around and across the top of the boiler down the other outer side of the opposite water leg 6, around the other water passage 7, and thence down the other supporting leg 25 to the floor line. A branch rib 45 31 extends from said water passage 7 along the inner side of the water leg 6 to provide a closed fire box and magazine throat, joining the rib 30 at the upper end of said water leg. It will thus be clear that the branch rib 31 furnishes a means of creating the substantially coextensive surface 11, when the sections are assembled, which positively directs the coal from the magazine 5 to and onto the grate. 50

There is also provided a rib 32 on the other side of the fuel magazine throat which extends around the steam outlet 13 and creates a surface on the other side of the magazine for the ready passage of fuel thereover. 55 Lastly there is provided a plurality of

aligned ribs 33 placed immediately below the flue passages 9 to substantially and effectively form a roof for the combustion chamber 35. These ribs are, however, so disposed as to create small passages 34 therebetween as well as between the ribs 30 and 32 as clearly shown in the drawings for the purpose of permitting some of the gases of combustion to pass directly to the flue passages 9, as well as to maintain a higher degree of heat within said flue passages. 70

The grate may be composed of two members, such as indicated at 40 and 41, for each water section and each member provided with a depending arm 42 to which the shaker bars (not shown) are secured as well understood. The member 40 is recessed at its lower end to fit a lug 43 cast on the fire box side of the water leg 20 and at the lowermost end thereof. The grate is set at an 80 inclination of about 30° in connection with the magazine fuel feed principle of the boiler and therefore the other end of the grate is secured in place on the fire box side of the other water leg 6 at a point slightly 85 above the passage 7. With this set of the grate there will automatically occur a settling of the burned fuel on the grate with resultant sifting of ashes therethrough. 90

In the water leg 6 on the fire box side 95 there is cast a recess or pocket 45 located at the point where the surface 11 over which the fuel slides meets the grate and into this pocket is slipped the trunnion 46 at the upper end of the grate member 41. The fire 100 box side of the water leg 6 is reversely formed to provide a surface 47 forming an angle of approximately 120° with the surface 11 and parallel to the fire box surface of the other water leg 20. The back side of the 105 recess 45 is parallel to the surface 47, and the bottom wall of said recess is perpendicular to said surface.

It thus results that the grate bars can be quickly inserted in position by first placing the lower end thereof over the lug 43 and then dropping the trunnion 46 at the upper end thereof into the pocket 45, it being understood that said lug and said pocket are coaxially disposed with reference to the 110 grate bars and are centrally disposed with reference to each water section of the boiler. The ready removal of any grate section is accomplished by first disengaging the same 115 from the shaker bars and then reversing the steps above mentioned for inserting said grate. 120

Not only does this construction provide a simple and quick means for inserting and removing the individual grate sections, but it also provides a positive and uninterrupted feed of the fuel to the grate. In other words, the pocket 45 is formed at the junction of the surface 11 with the grate and the surface 47, so that the fuel will slide over 130

said surface 11 directly onto the grate and thence over the grate surface while being consumed.

By this invention there is provided a smooth flow of fuel to the grate with no shelves or pockets onto or into which the fuel collects before it passes to the grate. Therefore there is avoided the collection of a mass of fuel beyond the magazine throat of considerable dimension which is not immediately subjected to combustion temperatures, with the result that fires of greater heat intensity are made possible by the present invention.

By reversely inclining the surface 47 air is positively directed to the fuel as soon as it reaches the grate and consequently combustion starts immediately, or in other words all of the fuel on the grate is subjected to oxidation or consumption with resultant higher fire temperatures than heretofore possible. The position of the back and bottom walls of the pocket 45 makes said pocket self cleaning as will be evident, and any ash tending to accumulate at the lower end of the grate will not clog the support thereof with resultant displacement of said grate due to the lug 43 entering the recessed end of the grate. The lug 43 being circular provides substantially 360° of supporting contact during shaking and dumping operations so that it is impossible to dislodge the lower supporting end of the grate, and the pocket 45 is of such a depth that dislodgment of the upper supporting end is practically impossible during said operations.

From the foregoing it will thus be seen that by this construction which is peculiarly adapted to sectional boilers of the magazine feed type and having a single inclined grate that there is provided a water leg 20 constituting one side of the section and which extends to the top thereof as well as a chamber 8 in open communication with said water leg and extending across the upper half of said section. Also there is provided a fuel magazine disposed at the top of said section adjacent said chamber 8 but which lacks any water jacket about its top and outer side. A second water leg 6 is disposed on the other side of the section said water leg extending only to said fuel magazine and provided with an upper inclined surface 11 as well as a lower inclined surface 47, the lower surface being parallel with the inner surface of the lowermost end of the water leg 20. A hollow web 23 joins in open communication a depending portion 10 of the chamber 8 with the water leg 6, said depending portion 10 being inclined from the vertical toward the inclined surface 11 of the water leg 6 to form therewith a constricted throat 12 through which the fuel passes from the magazine 5 thereabove, and the upper surface of the hollow web adapted to form a floor for some of

the fuel in the magazine but inclined to the horizontal to direct fuel therefrom to said constricted throat so that practically all of the fuel from the magazine 5 may readily pass through the throat to the grate. Lastly there is provided the lug 43 extending from the inner or fire box side of the water leg 20, as well as a pocket 45 disposed in the fire box side of the other water leg 6 at the junction between the inclined surfaces 11 and 47 thereof, said lug and said pocket being disposed perpendicularly opposite each other due to the parallelism of the inner surfaces of said water legs, and constituting self cleaning supports for the grate members 40 and 41.

It will be noted that the leg 6 is of triangular shape and that the water passage therethrough is bent to follow the inner inclined surfaces 47 and 11 which are diverged at a point near the top of the high end of the grate members 40, 41. The outer side of the leg 6 is substantially flush with the solid outer wall of the fuel magazine 5 to form one side of the section. The top of the latter is formed by the top of the chamber 8 and the solid top wall of the magazine. With this construction all the water passages are so positioned that the heat from the fire will gradually increase the temperature of the water as it passes from the passages 7 and 21 to the chamber 8.

It is obvious that those skilled in the art may vary the details of construction as well as arrangements of parts without departing from the spirit of the invention and it is therefore not desired to be limited to the foregoing disclosure except as may be required by the claims.

What is claimed is:—

1. In a boiler construction of sectional magazine feed type with single inclined grate the combination of a water leg constituting one side of a section said leg extending to the top of said section; a second water leg constituting part of the other side of said section said leg extending substantially two-thirds of the distance to the top of said section and provided with an inclined inner surface; a chamber in open communication with said first named water leg and extending across the upper half of said section; an extension of said chamber depending therebelow and inclined towards the inclined surface of said second water leg to form therewith a constricted throat through which the fuel passes from a magazine therefor; a hollow web in open communication with and connecting said depending extension with the top of said second water leg; said web extending to a point near the grate outlets from said first and second named water legs and from said chamber to an adjacent section; and self cleaning grate supports on said water legs.

2. In a boiler construction of sectional magazine feed type with single inclined grate the combination of a water leg constituting

- one side of a section said leg extending to the top of said section; a chamber in open communication with said water leg and extending across the upper half of said section; a fuel magazine disposed at the top of said section adjacent said chamber and lacking a water-jacket about its top and outer side; a second water leg disposed on the other side of said section and extending only to said magazine said leg provided with an inclined inner surface; an extension of said chamber depending therebelow and inclined towards the inclined surface of said second water leg to form therewith a constricted throat through which the fuel passes from said magazine; a hollow web in open communication with and connecting said depending extension of said chamber with the top of said second water leg the upper surface of said web forming a flooring for some of the fuel in said magazine; outlets from said first and second named water legs and from said chamber to an adjacent section; and self cleaning grate supports on said water legs.
3. In a boiler construction of sectional magazine feed type with single inclined grate the combination of a water leg constituting one side of a section said leg extending to the top of said section; a chamber in open communication with said water leg and extending across the upper half of said section; a fuel magazine disposed at the top of said section adjacent said chamber and lacking a water-jacket about its top and outer side; a second water leg disposed on the other side of said section and extending only to said magazine said leg provided with an upper surface inclined inwardly; an extension of said chamber depending therebelow and inclined towards the upper surface of said second water leg to form therewith a constricted throat through which the fuel passes from said magazine; a hollow web in open communication with and connecting said depending extension of said chamber with the top of said second water leg the upper surface of said web forming a flooring for some of the fuel in said magazine but inclined to the horizontal to direct fuel therefrom to said constricted throat; outlets from said first and second named water legs and from said chamber to an adjacent section; and self cleaning grate supports on said water legs.
4. In a boiler construction of sectional magazine feed type with single inclined grate the combination of a water leg constituting one side of a section said leg provided with a lowermost end having an upper surface, said leg extending to the top of said section; a chamber in open communication with said water leg and extending across the upper half of said section; a fuel magazine disposed at the top of said section adjacent said chamber and lacking a water jacket about its top and outer side; a second water leg disposed on the other side of said section and extending only to said magazine said leg provided with an upper surface inclined inwardly and a lower surface inclined outwardly, the lower surface being substantially parallel to the upper surface of the lowermost end of said first water leg; an extension of said chamber depending therebelow and inclined towards the upper surface of said second water leg to form therewith a constricted throat through which the fuel passes from said magazine; a hollow web in open communication with and connecting said depending extension of said chamber with the top of said second water leg; outlets from said first and second named water legs and from said chamber to an adjacent section; a grate support formed on the upper surface of the lowermost end of said first water leg; and a second grate support formed on the lower surface of said second water leg opposite said first grate support.
5. In a boiler construction of sectional magazine feed type with single inclined grate the combination of a water leg constituting one side of a section said leg provided with a lowermost end having an upper surface, said leg extending to the top of said section; a chamber in open communication with said water leg and extending across the upper half of said section; a fuel magazine disposed at the top of said section adjacent said chamber and lacking a water jacket about its top and outer side; a second water leg disposed on the other side of said section and extending only to said magazine said leg provided with an upper surface inclined inwardly and a lower surface inclined outwardly, the lower surface being substantially parallel to the upper surface of the lowermost end of said first water leg; an extension of said chamber depending therebelow and inclined towards the upper surface of said second water leg to form therewith a constricted throat through which the fuel passes from said magazine; a hollow web in open communication with and connecting said depending extension of said chamber with the top of said second water leg the upper surface of said web forming a flooring for some of the fuel in said magazine but inclined to the horizontal to direct fuel therefrom to said constricted throat; outlets from said first and second named water legs and from said chamber to an adjacent section; a grate support comprising a lug formed on the upper surface of the lowermost end of said first water leg; and a second grate support comprising a pocket formed on the lower surface of said second water leg opposite said first grate support.
6. In a boiler construction of sectional magazine feed type with single inclined grate the combination of a water leg constituting one side of a section said leg extending to the top of said section; a second water leg constituting part of the other side of said section said leg extending substantially two-thirds of the distance to the top of said sec-

tion and provided with an inwardly inclined upper surface and an outwardly inclined lower surface; a chamber in open communication with said first named water leg and extending across the upper half of said section; an extension of said chamber depending therebelow and inclined towards the upper surface of said second water leg to form therewith a constricted throat through which the fuel passes from a magazine therefor; a hollow web in open communication with and connecting said depending extension of said chamber with the top of said second water leg; outlets from said first and second named water legs and from said chamber to an adjacent section; and male and female grate supports disposed opposite to each other, one of said supports formed in the lower surface of said second water leg.

7. In a boiler construction of sectional magazine feed type with single inclined grate the combination of a water leg constituting one side of a section said leg having an inwardly inclined upper surface; a second water leg constituting part of the other side of said section said leg having an inwardly inclined upper surface and an outwardly inclined lower surface said lower surface being substantially parallel to the said upper surface of the first mentioned water leg; water passage connecting the upper portions of both of said water legs and extending around one side to the bottom of the fuel magazine; outlets from said first and second named water legs as well as from said passage to an adjacent section; and oppositely disposed grate supports one in the said upper surface of the first water leg and the other in the lower surface of the second water leg.

8. In a boiler construction of sectional magazine feed type with single inclined grate the combination of a water leg constituting one side of a section said leg having an inwardly inclined upper surface; a second water leg constituting part of the other side of said section said leg having an inwardly inclined upper surface and an outwardly inclined lower surface said lower surface being substantially parallel to the said upper surface of the first mentioned water leg; a water passage connecting the upper portions of both of said water legs and extending around one side and the bottom of the fuel magazine; outlets from said first and second named water legs as well as from said passage to an adjacent section; and oppositely disposed grate supports in said water legs, one of said supports being at the juncture of the upper and lower surfaces of said second water leg.

9. A sectional boiler of the magazine feed type having an inclined grate; a water cham-

ber; a fuel magazine, the said chamber and magazine being located side by side at the top of a section, the top of the section above the fuel magazine and the outer side of the fuel magazine remote from the chamber being formed as solid walls; a hollow web communicating with the chamber and located at the bottom of the fuel magazine, the section having water passages at opposite sides thereof; a water leg forming a communication between one of the passages and the chamber and forming therewith one side of the section; and a water leg of constantly varying cross-section communicating with the other passage and the hollow web and connected with the outer solid wall of the fuel magazine to form the other side of the section.

10. A sectional boiler having an inclined grate; water legs extending along opposite sides of a section and having inner surfaces substantially perpendicular to the top of said grate, and supports formed on said surfaces for the ends of said grate.

11. A sectional boiler having an inclined grate; water legs extending along opposite sides of a section and having surfaces at opposite ends of the grate substantially perpendicular to the top thereof; a boss formed on one of the surfaces for supporting one end of the grate; and a recess formed in the other surface for supporting the other end of the grate.

12. A sectional boiler of the magazine feed type having an inclined grate; a water chamber; a fuel magazine, the said chamber and magazine being located side by side at the top of a section, the top of the section above the fuel magazine and the outer side of the fuel magazine remote from the chamber being formed as solid walls; a hollow web communicating with the chamber and located at the bottom of the fuel magazine, the section having water passages at opposite sides thereof; a water leg forming a communication between one of the passages and the chamber and forming therewith one side of the section; and a triangular shaped leg having a water passageway therethrough communicating with the other passage and having its outer side substantially flush with the solid outer wall of the fuel magazine to form the other side of the section and having its inner sides diverged from one another at a point near the top of the high end of the grate, the upper end of the passageway communicating with the hollow web and terminating adjacent the top thereof.

13. A sectional boiler of the magazine feed type having an inclined grate; a water chamber; a fuel magazine, the said chamber and magazine being located side by side at the top of a section, the top of the section above the fuel magazine and the outer side of the fuel magazine remote from the chamber be-

ing formed as solid walls, the section having water passages at opposite sides thereof; a water leg forming a communication between one of the passages and the chamber and forming therewith one side of the section; a water leg communicating with the other passage and having an inwardly bent water passageway provided with a rib substantially flush with the solid outer wall of the fuel 10 magazine to form the other side of the section and having its inner sides formed of unequal lengths and diverged from one another at a point near the top of the high end of the grate, the longer side of the bent passageway being connected with the solid outer wall of the fuel magazine to direct the fuel onto the grate; an extension depending from the chamber and inclined towards the said longer side to form therewith a constricted 20 throat for the passage of fuel from the magazine; and a hollow web forming a communication between the said extension and the upper end of the long side of the bent passageway, the upper surface of the web being inclined to facilitate the discharge of fuel 25 from the magazine.

14. An integral boiler section of substantially an inverted U shape comprising a water leg, a chamber communicating with the leg 30 and forming therewith one side and substantially half the top of the section; a fuel magazine formed beside the chamber and having its top wall formed as a continuation of the top of the chamber to complete the 35 top of the section, the said top wall and the outer side of the magazine remote from the chamber being formed as solid walls; a hollow web communicating with the chamber and located at the bottom of the fuel magazine; a water leg of constantly varying cross-section 40 having its outer side substantially flush with the solid side wall of the magazine to form the other side of the section, the upper part of the last mentioned water leg communicating with the hollow web and terminating adjacent the upper surface thereof, the said legs and chamber being provided 45 with outlets; and means integral with the water legs for supporting a grate.

15. A sectional boiler of the magazine feed type having an inclined grate; a fuel magazine located above the high end of the grate; and water legs extending along opposite sides of a section and having surfaces inclined substantially perpendicularly to the plane of the 55 grate for supporting the ends of the same, one of the water legs having a substantially straight surface inclined from a point adjacent the top of the high end of the grate to the fuel magazine whereby the fuel will be directed in a substantially straight path on to the grate.

16. A sectional boiler having a pivoted inclined grate; water legs extending along opposite sides of a section each leg having an

inner surface substantially perpendicular to the plane of the grate; means carried by one of said leg surfaces for supporting the lower end of the grate; and an open bearing for carrying the upper end of the grate, the bearing being formed as a recess in the other of said leg surfaces.

In testimony whereof we affix our signatures.
